UNIVERSAL STRIPPING ARRANGEMENT
FOR DIES

Clarence L. Hornberger, Manheim Township,
Lancaster County, Pa., assignor to Armstrong
Cork Company, Lancaster, Pa., a corporation of
Pennsylvania

Application July 30, 1945, Serial No. 607,768

10 Claims. (Cl. 164—110)

1

My invention relates to dies and more particularly to an arrangement for stripping died material from within the die cavity. The invention is particularly useful in connection with the shearing or shearing and piercing of sheet metals such as aluminum parts used in aircraft fabrication.

An object of my invention is to provide a stripping arrangement which is substantially universal in its application so that dies for shearing or piercing various outlines may be conveniently inserted and removed from the die set and positive stripping obtained, thus providing for economical fabrication of short runs of material.

Another object of my invention is to provide a stripping arrangement in the die set which will apply a substantial pressure to the material to be ejected in cooperation with mechanism associated with the cavity die assembly, which mechanism may be removed from the die set as a unit with the cavity die assembly, thus making convenient the insertion and removal of cavity dies for short runs while providing for a positive stripping action.

Other objects of my invention will become apparent with a consideration of the following detailed description.

In order that my invention may be more readily understood, I will describe the same in conjunction with the attached drawings in which:

Figure 1 is a sectional view illustrating the die set of my invention;

Fig. 2 is a top plan view of the die shoe with the cavity die and its backup plates removed in order to expose the stripping arrangement for illustration;

Figure 3 is a detailed sectional view showing one of the stripping pins in partially retracted position; and

Figure 4 is a perspective view of an article of the type which may be sheared and pierced with the die set of the present invention.

Referring first to Figure 1, the die consists essentially of a punch die assembly 2 and a cavity die assembly 3 which are adapted to be moved relatively to one another to effect a shearing or piercing operation or both upon a sheet of material disposed between the dies. The punch die assembly 2 includes a backup plate 4 to which the punch is attached by rivets 5, two being shown in Figure 1. The punch 2 and its backup plate 4 are unitary so that they may be readily inserted and removed from the die set. This is particularly advantageous where short runs

2

of items are made, such as frequently occur in airplane parts fabrication.

The punch and its backup plate 4 are held in position against a so-called waffle plate 5 by means of edge clamps 6 and 7 disposed at the transverse edges of the backup plate 4. The clamps 6 and 7 are attached to the waffle plate 5 by hollow head cap screws 8 and 9, one being shown in each side in Figure 1, but two being generally employed on each side as indicated in Figure 2 in order to firmly secure the punch in position against the waffle plate. Locating dowel pins 10 are provided for properly aligning the elements in the press. It will be noted that the dowel pins 10 extend through the backup plate 4 and the waffle plate 5 into a punch holder or die shoe 11. The waffle plate 5 is secured to the punch or die shoe holder 11 by hollow head cap screws 12.

20 The punch die assembly 2 is adapted for movement toward and away from the cavity die assembly 3 and, to provide for accurate movement, the customary guiding mechanism used in die sets may be provided. This includes cylindrical ways 15 which receive bushings 13 provided in openings 14 in the die shoe 11. The bushings 13 serve to guide the die assembly in its reciprocatory movement toward and away from the cavity die 3, sliding motion being effected on the upright ways 15. In the embodiment chosen for illustration, two ways 15 are provided, as best shown in Figure 2.

25 The cavity die 3 is secured to a backup plate 16 by means of rivets 17 which pass through the cavity member 3 and the backup plate 16. A second backup plate 18 is provided to support the piercing punches 19 which pass through the backup plate 16 and lie in engagement with the backup plate 18. The cavity die assembly, including the cavity die 3, the backup plates 16 and 18, and the auxiliary equipment is demountable as a unit in the same manner as the punch die assembly 2. Edge clamps 20 are provided for clamping the cavity die assembly to a die shoe 21 by means of hollow head cap screws 22, and dowel pins 23 serve to align the cavity die members with respect to the die shoe 21. The piercing punches 19 cooperate with die openings 24 provided in the punch element 2 and serve 30 in cooperation to pierce holes in sheet material disposed between the die elements.

A spacer plate 25 is positioned between the die shoe 21 and a bolster plate 26 and dowel pins 27 are provided for properly aligning the spacer plate 25 and die shoe 21. Hollow head cap screws

28 secure the spacer plate 25 and die shoe 21 together. The whole mechanism above described including and extending above the spacer plate 25 constitutes a die set which may be removed from the operating punch press or inserted therein as a unit. When the die set is assembled in a conventional press, cap screws 29 are provided for bolting the die set to the bolster plate 26 of the press as shown in Figure 1.

The cavity die assembly 3 includes a stripper plate 30 which is disposed within the opening in the cavity die. The plate 30 is provided to eject the sheared piece from within the die opening, and when relatively heavy metals are sheared, it is difficult to remove the piece from within the cavity die, particularly if there are a number of small pierced openings in the piece and if the area at the periphery of the piece in engagement with the die is relatively extensive compared with the flat surface area in engagement with the stripper plate.

In order to provide for positive ejection of the formed piece by means of the stripper plate 30, there is provided, in accordance with the present invention, a stripper mechanism including a pneumatic die cushion 47 which may be attached to the lower platen of the press and applies yielding force to a piston or floater 31 which is slideable within an opening 32 in the bolster plate 26. The floater 31 is provided with a radial extension 33 which provides a shoulder 34 for engagement with the bottom of a recess 35 counterbored in the bolster plate 26. The floater 31 carries a hardened steel plate 36 which is of a diameter greater than the diameter of the floater 31 and is free to slide within a counterbore 37 provided in the spacer plate 25 and is limited in its downward movement by a shoulder 38 which is formed in the spacer plate 25.

In order to provide for universal stripping, regardless of the shape or configuration of the piece being died at any particular time, thus making possible the use of a single stripping arrangement for any die cavity assembly which may be attached to the die shoe, I provide a multiplicity of closely spaced openings in the die shoe 21 and in each of these there is received a stripper pin 39 which is preferably hardened and ground to size. The stripper pins 39 rest upon the hardened steel plate 36 and certain of these pins engage stripper plate holders 40 which are secured to the stripper plate 30 and pass through the backup plates 16 and 18 and into the die shoe 21 as shown in Figure 3 where the stripper plate holders 40 are illustrated in detail. The holders 40 consist of a main body 41 which is shouldered at 42 and the reduced section is riveted as indicated at 43 to the plate 30. The main body 41 passes with clearance through the backup plates 16 and 18 and is shouldered and provided with a screw thread which receives a hexagonal nut 44. The assembly is affected by riveting the stripper plate holder 40 to the stripper plate 30 by the rivet 43, the main body 41 being then passed through openings provided in the backup plates 16 and 18. The nut 44 is then applied and draws the stripper plate 30 into its desired final position. A resilient stripping material 45, such as a body of cork composition, may be interposed in the die cavity between the stripper plate 30 and the backup plate 16 to hold the parts in the position shown in Figure 1 with the stripper plate 30 in its extended position even when the die set is removed from the press. (In Figures 1 and 3 the floater 31 and the hardened steel plate 36 are shown in

slightly retracted position so that there may be clearly shown the disposition of the stripper plate holders 40 and the stripper pins 39. In normal operation the arrangement will preferably be such that the stripper pins 39 will just clear the nuts 44 when the floater 31 is elevated to its uppermost position by the pneumatic die cushion 47.)

The die shoe 21 is counterbored as indicated at 46 to receive the stripper plate holders and the nuts which are associated with them. This is best shown in Figure 3.

In the operation of my die set, the die shoe 11 and the waffle plate 5 are secured together by the bolts 12. The die shoe 21, spacer plate 25, and stripper pins 39 are also set up and the screws 29 are screwed down to secure the assembly to the bolster plate of the press. This is a conventional die set up. An appropriate punch assembly 2 is inserted into the set, being aligned by the dowel pins 10 and clamped by the edge clamps 6 and 7. A corresponding cavity die assembly, including the cavity member 3, the backup plates 16 and 18, the stripper plate and its holders 40, together with associated mechanism is affixed to the die shoe 21, being aligned by dowel pins 23 and held in position by edge clamps 20. The stripper plate holders 40 are disposed within the counterbored recesses 46 of the die shoe 21. The pneumatic die cushion 47 will then be actuated and elevated until it is in engagement with the bolster plate 26. This will bring the stripper pins 39 to a position where those which engage the stripper plate holders 40 will lie in close proximity thereto. Air will be constantly supplied to the die cushion so as to maintain a constant loading on the pins 39. A sheet of material to be fabricated will be disposed in the opening between the punch 2 and the cavity 3 and the punch and its associated mechanism will be moved toward the cavity 3, sliding along ways 15, force being applied through the die shoe 11 by the ram of the punch press. As the dies close, the punch 2 will force the metal into the opening in the cavity 3 effecting a shearing of the metal into an outline corresponding to the shape of the opening in the cavity die 3. The force applied to the punch 2 through the sheared metal, being greater than the die cushion loading, will depress the stripper plate 30, and the stripper plate holders 40 will engage their corresponding stripper pins 39 which will in turn apply force to the hardened steel plate 36, the floater 31, and the pneumatic die cushion 47; the whole being depressed simultaneously. The piercing punches 19 will effect a piercing of the metal to provide openings therein and the punched out portions will move through the openings 24 in the punch 2 and will eventually be disposed in the openings in the waffle plate 5 from whence they may be blown in the manner well known in the art.

As the dies are opened, the pneumatic die cushion 47 will apply force to the pins 39 through the hardened steel plate 36 and the floater 31 and the stripper plate holders 40 will move the stripper plate to its normal position with the nuts 44 in engagement with the backup plate 18. The force applied by the pneumatic die cushion 47 will depend upon the thickness of the metal being operated upon, the area of the periphery of the sheared metal in engagement with the dies, and other factors. A force of several thousand pounds has been found effective for ejecting a sheared and formed piece of .080" thickness 24 S. T. aluminum as shown in Figure 4. It will be noted that the piece there shown has a large

peripheral area 48 and is provided with three relatively small pierced openings 49. Such a piece would be difficult to remove with an ordinary resilient stripper arrangement.

From the foregoing description, it will be clear that with my die set and stripping arrangement, practically any shape of piece may be conveniently sheared or pierced or both, utilizing a universal stripper arrangement to remove the piece from within the die cavity and away from the piercing punches. All that is necessary in fabricating a die for use with my universal stripper is to predetermine the position of the stripping pins 40 so that they may be received in certain of the bores 46 provided in the die shoe. By reference to Figure 2 it will be clear that there are many bores 46 and that they are closely spaced so that it will be a very simple matter to locate the stripper plate holders in any desired location, regardless of the shape of the piece being sheared or its size, provided, of course, it falls within the limits of the size of the die set. In some dies only two stripper plate holders and corresponding pins may be utilized, whereas in others as many as six or more may be required.

It will be noted that while the counterbores 46 are relatively closely spaced, there is a substantial area of metal 50 surrounding each opening 46. This insures that the cavity die 3 will be properly supported and prevented from springing under the terrific forces encountered in the shearing and piercing of thick metal sheets. This makes possible the use of thin backup plates 16 and 18 for supporting the cavity die 3 and, in fact, these may be formed of steel plate about $\frac{1}{4}$ " thick. Such dies are commonly used in the aircraft industry and are desirable because they are inexpensive to manufacture and are wholly acceptable for the shearing and piercing of aluminum and similar metals.

While I have illustrated and described a preferred embodiment of my invention, it will be understood that the same may be otherwise embodied and practiced within the scope of the following claims.

I claim:

1. In a die set of the type in which a punch die assembly and a cavity die assembly are mounted for relative motion to bring the dies together to work a sheet of material disposed therebetween and in which the cavity die assembly is provided with a stripper plate for ejection of the worked sheet from within the cavity die, a universal stripping arrangement adapted for actuation of stripper plates of various shapes and sizes mounted in said die set comprising a plurality of stripping pins received within closely spaced chambers formed in a die shoe and terminating in the surface of said die shoe, substantially the entire area at said surface being formed of chambers spaced by relatively thin walls, and means for moving said pins in unison to stripping position.

2. In a die set of the type in which a punch die assembly and a cavity die assembly are mounted for relative motion to bring the dies together to work a sheet of material disposed therebetween and in which the cavity die assembly is provided with a stripper plate for ejection of the worked sheet from within the cavity die, a universal stripping arrangement adapted for actuation of stripper plates of various shapes and sizes mounted in said die set comprising a plurality of stripping pins received within closely spaced chambers formed in a die shoe and terminating in the surface of said die shoe, substantially the entire

stripping area at said surface being formed by chambers spaced by relatively thin walls to support the cavity die assembly in the working area thereof, and means for yieldingly holding said stripper pins in stripping position, said means being retractable upon the application of pressure to one or more of said stripper pins.

3. In a die set of the type in which a punch die assembly and a cavity die assembly are mounted for relative motion to bring the dies together to work a sheet of material disposed therebetween and in which the cavity die assembly is provided with a stripper plate for ejection of the worked sheet from within the cavity die, a universal stripping arrangement adapted for actuation of stripper plates of various shapes and sizes mounted in said die set comprising a plurality of stripping pins received within closely spaced chambers formed in a die shoe and terminating in the surface of said die shoe, substantially the entire stripping area at said surface being formed of chambers spaced by relatively thin walls to support the cavity die assembly in the working area thereof, and an air cushion yieldingly holding said stripper pins in stripping position.

4. In a die set of the type in which a punch die assembly and a cavity die assembly are mounted for relative motion to bring the dies together to work a sheet of material disposed therebetween and in which the cavity die assembly is provided with a stripper plate for ejection of the worked sheet from within the cavity die, a universal stripping arrangement removable from the die set as a unit and adapted for actuation of stripper plates of various shapes and sizes mounted in said die set comprising a die shoe, a spacer plate attached to the die shoe, a plurality of stripping pins received within closely spaced chambers formed in the die shoe and terminating in the surface of said die shoe, substantially the entire stripping area at said surface being formed of chambers spaced by relatively thin walls to support the cavity die assembly in the working area thereof, a stripper pin actuating plate reciprocable within said spacer plate to move said stripper pins in unison to stripping position, and means for limiting movement of said pin actuating plate in its reciprocatory movement.

5. In a die set of the type in which a punch die assembly and a cavity die assembly are mounted for relative motion to bring the dies together to work a sheet of material disposed therebetween and in which the cavity die is supported by a relatively thin backup plate and is provided with a stripper plate for ejection of the worked sheet from within the die cavity, a universal stripping arrangement adapted for actuation of stripper plates of various shapes and sizes which may be mounted in said die set, comprising a plurality of stripping pins received within closely spaced chambers formed in a die shoe, said chambers terminating in the surface of said die shoe which receives said backup plate, said chambers constituting a major portion of the stripping area of the die shoe and spaced by walls which are adapted to support the cavity die assembly, and means for yieldingly urging said stripper pins in unison toward said cavity die assembly engaging surface of the die shoe.

6. In a die, a die shoe, a cavity die assembly supported upon the die shoe and demountable therefrom, said assembly including a cavity die member, a stripper plate for said cavity die member, and a plurality of stripper plate holders adapted to move the stripper plate to stripping

position, a plurality of chambers in the die shoe adapted to receive the ends of said stripper plate holders, stripper pins movable within said chambers to engage said stripper plate holders, and yielding means for applying force to said stripper pins to urge said stripper plate to stripping position.

7. In a die, a die shoe, a plurality of closely spaced chambers formed throughout a major portion of the surface of the die shoe in the area to receive a cavity die assembly, said chambers being adapted to receive the stripper plate holders of said cavity die assembly, stripper pins movable within said chambers, and means for yieldably urging said stripper pins to stripping position.

8. In a die, a universal stripping arrangement comprising a die shoe, a plurality of closely spaced chambers separated by walls of material terminating in a common plane to support a cavity die assembly, stripper pins movable within said chambers to engage complementary stripper plate holders, and means for yieldingly urging said stripper pins to stripping position.

9. In a die, a universal stripping arrangement comprising a die shoe, a plurality of closely spaced openings in the die shoe extending from the top to bottom thereof, said openings being enlarged adjacent the cavity die assembly supporting surface thereof to receive stripper plate holders forming part of a cavity die assembly, a plurality of stripper pins in said openings and reciprocable therein to move in one direction upon movement of the stripper plate of the cavity die assembly into the cavity die and movable in the opposite direction to apply force to said stripper plate through said stripper plate holders in move-

ment of said stripper plate to stripping position, and an air cushion yieldingly urging said stripper pins into stripping position and retractable upon the application of force to the stripping pins when the stripper plate is moved within the cavity die opening.

10. In a die, a die shoe, a cavity die assembly supported on the die shoe and demountable therefrom, said assembly including a cavity die member, a stripper plate for the cavity die member, a backup plate to which the cavity die member is attached, stripper plate holders secured to said stripper plate and passing slidably through openings provided in said backup plate, means on said stripper plate holders limiting movement of said stripper plate in stripping, a plurality of closely spaced chambers in the die shoe adapted to receive said stripper plate holders, stripping pins movable within said chambers to engage said stripper plate holders, and means for moving said stripper pins to stripping position.
